US00D997161S

(12) **United States Design Patent** (10) **Patent No.:** **US D997,161 S**
(45) **Date of Patent:** **** Aug. 29, 2023**

(54) **SOLID STATE DRIVE MEMORY DEVICE**

(71) Applicant: **SAMSUNG ELECTRONICS CO., LTD.**, Suwon-si (KR)

(72) Inventors: **Yusuf Cinar**, Suwon-si (KR); **Jae Hong Park**, Suwon-si (KR); **Han Hong Lee**, Suwon-si (KR); **Seon Gyun Baek**, Suwon-si (KR); **Won-Gi Hong**, Suwon-si (KR)

(73) Assignee: **SAMSUNG ELECTRONICS CO., LTD.**, Suwon-si (KR)

(**) Term: **15 Years**

(21) Appl. No.: **29/805,545**

(22) Filed: **Aug. 27, 2021**

(57) **CLAIM**

The ornamental design for a solid state drive memory device, as shown and described.

DESCRIPTION

FIG. 1 is a front perspective view of a solid state drive memory device showing my new design;

FIG. 2 is a front view thereof; and,

FIG. 3 is a top plan view thereof.

The evenly dashed broken lines in the figures depict portions of the solid state drive memory device that form no part of the claimed design.
